UNITED STATES PATENT OFFICE.

FRANK J. O'LEARY, OF DETROIT, MICHIGAN, ASSIGNOR TO PENBERTHY INJECTOR CO., OF DETROIT, MICHIGAN, A CORPORATION OF MICHIGAN.

EJECTOR.

1,109,593.

Specification of Letters Patent.

Patented Sept. 1, 1914.

Application filed November 22, 1912. Serial No. 732,816.

To all whom it may concern:

Be it known that I, FRANK J. O'LEARY, a citizen of the United States of America, residing at Detroit, in the county of Wayne 5 and State of Michigan, have invented certain new and useful Improvements in Ejectors, of which the following is a specification, reference being had therein to the accompanying drawings.

10 This invention relates to improvements in lifting ejectors and its object is to increase, by simple and efficient means, the discharge per unit of time, of ejectors constructed in an old and well known manner; the invention 15 consisting in the matters hereinafter set forth and more particularly pointed out in the claim reference being had to the accompanying drawing in which,

Figure 1 is a vertical longitudinal section 20 through an ejector embodying the invention; Fig. 2 is a transverse section of the same on the line 2—2 of Fig. 1; and Fig. 3 is an elevation of the combining tube detached.

As shown in the drawing 1 represents a 25 suitable casing having a water inlet 2 at its lower side into which is screwed a pipe forming a conduit in which the water is raised by suction in the pipe 2. Coupled to one end of the casing is a steam pipe 3 and 30 a nozzle 4 projects into the casing from the end of the pipe to direct a jet of steam into the flaring open end 5 of a combining tube 6 which is secured in the opposite end of the casing with its flaring end adjacent to 35 the end of the nozzle, said tube being screwed or otherwise secured in the end of the casing and arranged in the usual manner.

40 All of the foregoing described parts and their arrangement are old and well known and this invention consists in forming the combining tube with one or more longitudinal slits 7 in its side walls within the body of the casing, said slits extending from near 45 the flaring end of the tube adjacent to the nozzle to near the end of the casing.

In operating the device a steam pressure 50 is turned on through the pipe 3 and a jet of steam of very high velocity is projected by the nozzle 4 into the open end of the combining tube 5. The steam passing through and out of the end of the combining tube with great rapidity will at once

cause a vacuum or partial vacuum in the chamber of the casing and water will thus 55 be raised through the inlet pipe into the casing and will begin to flow into the open end of the combining tube around the nozzle and out with the steam. As soon as the stream of water is established the jet of 60 steam entering this stream combines therewith in the combining tube and is condensed. By reason of the condensation of the steam as it is projected into the stream of water at the flaring end of the combining 65 tube, the stream of water entering the tube around the nozzle is not sufficient to fill the outlet end of the combining tube. By providing the slits 7 in said tube additional water is drawn in from the casing through 70 the slits as the stream of steam and water passes outward and contract during such outward movement by reason of the condensation of the steam into water. This contraction of the outflowing stream begins to take place 75 just as soon as the steam strikes the water near the open end of the combining tube and continues during the passage of the stream through the tube. These slits thus permit additional water to flow laterally into the 80 tube and make up for the contraction of the stream caused by the rapid condensation of the steam contained in it, thus greatly increasing the lifting capacity of the device.

Obviously changes may be made in the 85 form and construction of the casing and other parts of the device, and the combining tube may be provided with one or more slits therein, as desired, without departing from the spirit of my invention and I do not limit 90 myself to the form and construction shown.

Having thus fully described my invention what I claim is:

In an ejector, the combination of a casing 95 having a fluid inlet, and jet nozzle extending into the casing through one end thereof, of a combining tube extending into the opposite end of the casing in axial alinement with the jet nozzle and having a flaring inner end adjacent to and of greater diameter than the end of the nozzle and said combining tube being formed with diametrically opposed narrow slits in its side extending longitudinally thereof within the casing from adjacent to its open end to a point near the 100 end of the casing through which the tube ex-

tends, one of said slits confronting the fluid inlet of said casing and the other slit the wall opposite said fluid inlet, whereby back pressure from said fluid inlet is admitted to
5 said tube to combine with the direct pressure from said fluid inlet at a point in axial alignment with said jet nozzle.

In testimony whereof I affix my signature in presence of two witnesses.

FRANK J. O'LEARY.
